UNITED STATES PATENT OFFICE.

EMIL A. CUPPERS, OF NEW HAVEN, CONNECTICUT, ASSIGNOR TO SARGENT & CO., OF SAME PLACE.

DESIGN FOR COFFIN-SCREWS.

SPECIFICATION forming part of Design No. 11,786, dated May 25, 1880.

Application filed April 26, 1880. Term of patent 14 years.

To all whom it may concern:

Be it known that I, EMIL A. CUPPERS, of New Haven, in the county of New Haven and State of Connecticut, have invented a new Design for Coffin-Screws; and I do hereby declare the following, when taken in connection with the accompanying drawings, and the letters of reference marked thereon, to be a full, clear, and exact description of the same, and which said drawings constitute part of this specification, and represent, in—

Figure 1, a side view; Fig. 2, a top view of the plate detached.

This invention relates to a design for coffin-screws, applicable also as lifters for the coffin-lid; and it consists in the configuration and ornamentation, as shown in the accompanying illustration, and hereinafter described.

The design represents a bird as in the act of alighting upon the screw-plate. The bird serves as the screw-head proper, and the plate as a rest for the head.

The plate represents a bunch of lilies of the

valley, the leaves of the plant lying flat and springing from one stem, and showing the flowers as lying upon the leaves.

This screw-head may be used with a different plate or the plate with a different head. The design is, therefore, not to be understood as for a combination of this particular head and particular plate, but that there shall be some plate with the head.

I claim—

1. The design for coffin-screw head, consisting of the representation of a bird as in the act of lighting upon the screw-plate, as shown in the accompanying illustration.
2. The design for coffin-screw plate, consisting of the representation of leaves and flowers of the lily of the valley, as shown in the accompanying illustration.

EMIL A. CUPPERS.
